Primary Examiner — Christian P. McLean(74) *Attorney, Agent, or Firm* — Leason Ellis LLP(57) **CLAIM**

The ornamental design for a display screen with transitional graphical user interface, as shown and described.

DESCRIPTION

FIG. 1 is a first image in a sequence of a display screen with transitional graphical user interface showing the new design; FIG. 2 is a second image thereof; FIG. 3 is a third image thereof; FIG. 4 is a fourth image thereof; and, FIG. 5 is a fifth image thereof.

The appearance of the animated graphical user interface sequentially transitions between the images shown in FIGS. 1-5. The process or period in which one image transitions to another image forms no part of the claimed design.

The broken lines of uneven length illustrate the display screen and form no part of the claimed design. The remaining broken lines illustrate portions of the graphical user interface that form no part of the claimed design.
